ROTATABLE DISPLAY RACK FOR PENS AND THE LIKE

Toma Georgieff, 1742 Maple Ave.,
Granite City, Ill. 62040

Filed Aug. 20, 1965, Ser. No. 86,663

Term of patent 14 years

(Cl. D80—9)

FIG. 1

FIG. 3

FIG. 1 is a side elevation of a rotatable display rack for pens and the like embodying my new design.

FIG. 2 is a top plan view thereof.

FIG. 3 is a sectional view taken along line 3—3 of FIG. 1.

I claim:

The ornamental design for a rotatable display rack for pens and the like, substantially as shown.
